UNITED STATES PATENT OFFICE.

TULLEY O'MALLEY, OF CORDOVA, TERRITORY OF ALASKA.

PORTABLE BANDSAW.

Application filed April 17, 1922. Serial No. 553,405.

To all whom it may concern:

Be it known that I, TULLEY O'MALLEY, a subject of Great Britain (who has declared his intention to be a citizen of the United States), residing at Cordova, in the Cordova Precinct and Territory of Alaska, have invented certain new and useful Improvements in Portable Bandsaws, of which the following is a specification.

10 The invention has reference to saw machines and particularly to improvements in the construction and design of machines of the band saw type.

15 The main purpose and object of the invention is to provide an improved band saw machine of a portable character adapting it to be conveniently used for under-water work cutting off piles, and sawing trees or wood.

20 An additional object is to provide a band saw having means for adjusting the cutting saw and utilizing air pressure as a propelling force.

25 A further object of the invention is to provide a device of the above character that is simple in construction, strong and durable and which it is believed may be manufactured at a reasonably low cost.

30 Various other objects and advantages of the invention will become apparent during the continuance of the following description.

In the drawings:—

Figure 1 is a diagrammatic view of the invention, partly in plan and partly in section.

35 Figure 2 is a bottom plan view.

Figure 3 is a horizontal cross section of the frame taken on line 3—3 of Figure 1.

Figure 4 is an enlarged detail sectional view illustrating the manner in which the 40 screw rod is locked to its adjusted positions.

The invention is embodied in a supporting frame of adjustable sections, one of which includes an elongated guide rail 10 having a relatively thickened portion 11 adjacent one end which portion is provided on its inner side with a longitudinally extending groove 12 for a purpose to be hereinafter explained.

50 Bolted or otherwise fastened to the shoulder portion 11 of the guide rail and on opposite sides so as to be in spaced parallel relation to one another are supporting plates 13 and 14. Positioned between the plates adjacent their outer end and fastened to each is a spacing block 15. These plates ex-

tend at right angles to the guide rail and are adapted to support the motor casing 16. This casing is preferably located at an intermediate point on the plate and is supported by suitable brackets 17 extending cross wise between the plates and suitably fastened to each as indicated at 18. Connected to one side of the motor casing is a valve member 19, provided with an operating lever 20 which serves to control the pressure admitted into the casing through the air hose 21.

Extending centrally through casing 16 is a drive shaft 22 which has its forward end journaled in block 15 and any suitable mechanism may be encased within housing 16 for rotating the shaft under pressure of the air admitted through hose 21.

55 Affixed to the other end of shaft 22 is a drive gear 23, held in place by nut 24. This drive gear meshes with pinion 25, the latter being integral with friction wheel 26. The wheel and pinion are rotatably supported by a bearing bracket 27 fastened to block 15. Wheel 26 supports one end of an endless band saw 28, the other end of which is similarly supported by a second friction wheel 29 mounted to turn freely on bearing 30 at the end of supporting arm 31. Each friction wheel is held in place on its respective bearing by means of a nut 32. Arm 31 is carried by a tubular slide 33 extending at right angles from one end thereof and having a square bore for receiving the square guide rail 10.

80 Slide 33 is adapted to move longitudinally of the guide rail for adjusting arm 31 at various distances from supporting plates 13 and 14 of the opposite frame-section so that band saws of various lengths may be employed. This arrangement also permits the adjustment of arm 31 outwardly of the frame for spacing the friction wheels apart sufficiently to hold saw 28 taut and under proper tension. This adjustment is accomplished by means of a screw rod 34 extending parallel with guide rail 10 with one end in a suitable socket extension 35 formed integral with slide 33, the terminal of the rod at such end being preferably headed, as at 36, to provide a swivel connection with the socket, thereby locking the slide and screw rod together. The opposite end of rod is threaded as indicated at 37 and extends within groove 12 passing through a thread-

ed opening 38 at the lower end of shoulder portion 11. A hand wheel 39 is formed integral with the outer threaded end of the screw rod and permits the latter to be manually turned for adjusting slide 33 longitudinally of rail 10 to obtain the required adjustment.

After the screw rod has been turned the necessary amount it may be locked against 10 further movement by means of a locking screw 40 carried by the socket extension 35 as shown in Figure 1 of the drawings.

In operation the saw is supported by two operators, one at each end of the frame to 15 hold the saw up to the pile, tree or other object being sawed. The frame is preferably constructed of some light durable material to provide a saw of the class described which can be easily handled and transported from 20 place to place by one or two persons and, it is obvious that by employing air pressure as a propelling medium much of the weight usually accompanying the motive power is eliminated, thereby increasing the lightness 25 of the machine without depreciating its driving power.

From the foregoing it is believed that the advantages and novel features of my invention will be readily understood and therefore 30 further detailed description is deemed unnecessary.

What is claimed is:

1. A band saw machine comprising a supporting frame of adjustable sections, one of 35 which includes a guide rail while the other includes a slide mounted for longitudinal adjustment along the said rail, an endless band saw means, means on the slide for rotatably supporting one end of the saw, 40 means on the rail for rotatably supporting the other end of the saw, an adjusting screw rod having a threaded portion adapted to thread through a portion of the frame providing the guide rail, and a head on said 45 screw rod adapted to engage the slide for moving the same in either direction along said guide rail.

2. A band saw machine comprising a supporting frame of adjustable sections, one of

which includes a guide rail while the other 50 includes a slide mounted for longitudinal adjustment along the said rail, an endless band saw means, means on the slide for rotatably supporting one end of the saw, 55 means on the rail for rotatably supporting the other end of the saw, an adjusting screw rod having a threaded portion adapted to thread through a portion of the frame section providing the guide rail, a head on said screw rod adapted to engage the slide for 60 moving the same in either direction along said guide rail, and a locking screw cooperative with said slide for constituting an end abutment for the head, and adapted for being screwed tightly against said head to 65 force the same against the slide to lock the adjusting screw rod against rotation.

3. A band saw machine comprising the following elements in combination, a friction wheel supporting member, said supporting 70 member including a pair of side plates adapted to support therebetween a power applying means, a friction wheel supported upon said member, means for rotating said friction wheel also mounted upon said supporting member, a guide rail secured to said supporting member, a supporting arm cooperative with said supporting member, a friction wheel mounted upon said arm, a slide member secured upon said arm and 75 adapted to longitudinally slidably engage said guide rail, a band saw operable over said friction wheels, an adjusting screw rod having a threaded portion adapted to thread through a portion of the guide rail and including a shank portion freely rotatable in a bore therefor in said slide member, a head on said screw rod freely rotatable at times in a socket formed therefor in said slide member, and a locking screw cooperative 80 with the shoulders formed by said socket in forming thrust abutments for said head and for being screwed tightly against said head to force the same against said shoulders to lock the adjusting screw against rotation.

In testimony whereof I affix my signature.

TULLEY O'MALLEY.
